E. O. GAY.

PLow.

APPLICATION FILED FEB. 18, 1911.

992.556.

Patented May 16, 1911.

UNITED STATES PATENT OFFICE.

EDWARD O. GAY, OF RED SPRINGS, NORTH CAROLINA, ASSIGNOR OF ONE-THIRD TO WILLIAM JONES AND ONE-THIRD TO MARTIN MCKINNON, BOTH OF RED SPRINGS, NORTH CAROLINA.

PLOW.

992,556.

Specification of Letters Patent. Patented May 16, 1911.

Application filed February 18, 1911. Serial No. 609,312.

To all whom it may concern:

Be it known that I, EDWARD O. GAY, a citizen of the United States, residing at Red Springs, in the county of Robeson and State of North Carolina, have invented certain new and useful Improvements in Plows, of which the following is a specification.

My present invention relates to improvements in that class of plows more especially designed as cotton plows and in which the plow point is so mounted that it can be adjusted to the desired angle with respect to the line of draft and according to the condition of the soil to be turned and the particular work to be performed thereby.

Plows have heretofore been provided that have means for tilting the plow point to the angles desired relatively to the shoe or runner and such operation accomplished without stopping the plow, and in many types of plows such adjustments of the plow point is effected by swinging lever and rack devices. From practical experience with plows of the general type referred to I have found their structure and operation open to objections, partly for the reason that the construction is costly and particularly for the reason that in setting the plow point to the different angles, the relative positions of the point and the runner or shoe changes, and to such an extent that the point when set to dig a shallow furrow frequently rises above the plane of the riding face of the runner or shoe, or when set to dig a deep furrow it projects so far below the said runner that a proper guiding or bearing of the plow is rendered difficult.

My invention, which primarily has for its object to provide a construction of plow cheap as to cost, and in which the set of the point is easily effected while running the plow, more especially has for its purpose to provide for setting the said plow point either shallow or deep without changing the relative positions of the point and the runner, or in other words, in such manner that the plow point and the riding face of the runner always remain in the same horizontal alignment so the runner or shoe always travels in and has a solid bearing on the bottom of the furrow made by the plow.

My invention consists in the special construction of plow hereinafter fully described, specifically set out in the appended claims

and illustrated in the accompanying drawings, in which:

Figure 1, is a perspective view of my improved plow, the plow point being shown adjusted to its most shallow position. Fig. 2, is a side elevation thereof, the parts being in the position shown in Fig. 1, the plow point and other parts being shown in section. Fig. 3, is a side elevation that shows the plow point adjusted to its maximum vertical or digging position, and illustrates the relation of the point and the runner. Fig. 4, is a vertical cross section on the line 4—4 of Fig. 3. Fig. 5, is a perspective view of the plow point and the slotted sliding shank or head, hereinafter referred to.

The plow beam 1 carries a draft clevis 1^a at the front end of any approved type and its rear end 1^b is curved downwardly to form a standard that is rigidly bolted to the rear end of the runner 2, which carries a removable shoe or riding member 20 that is connected to the runner 2 by the bolt and nut connection (see Fig. 2), so it may be removed when worn, and a new shoe substituted therefor. The plow standard 3 of my present construction of plow terminates at the upper end in a handle 3^a, while its lower end is bifurcated, as at 3^b to straddle the beam and the front end of the said runner 2, to which it is pivotally connected by the bolt 3^c.

The plow beam at that part within the sweep of the standard 3, is formed with a pendent enlargement 1^d that is formed with an upper or guide slot 4 that is concentric with the pivot point of the standard 3, and a second or lower slot 5 which is eccentric with respect to the said slot 4 and the pivot point of the standard, the under edge of the said pendent portion being curved on an arc concentric with the lower slot 5 for the purpose presently explained.

9 designates the plow point of any approved shape, and it is bolted onto and is movable with a movable head casting 6 slidably held with the bifurcated end of the standard and is vertically movable therein, as the standard is swung backwardly or forwardly to adjust the vertical inclination of the plow point.

For effecting the shifting of the plow point, relatively to the standard, and in such manner that the penetrating point of

the plow remains in the same plane with respect to the drag or shoe face of the runner, the head 6 has its upper end bifurcated to form side arms 60 that straddle the pendent extension of the plow beam and the eccentric slot 5 therein, and the upper ends of the arms 60 carry a cross bolt 61 that rides in the said slot 5, a cross piece 62 being also secured to the upper ends of the straddle arms 60 that engages the lower edge of the pendent beam portion, as is best shown in Figs. 2 and 3.

7 designates a cross pin on the standard that passes through the slot 4 and guides the said standard in its forward and backward adjustments.

The upper edge of the beam has a rack portion 8 concentric with the pivot axis of the standard and with it cooperates the usual spring pawl device 80, operated by the hand piece 81, in the usual manner.

10 designates the plow handles and 11 the side braces therefor.

By reason of the peculiar construction and arrangement of the several parts as shown and described it will be apparent from the drawings that when the plow standard is swung backwardly to give the plow its lowest inclination for shallow digging, the head that carries the plow point will, by reason of its peculiar connection with the eccentric slot 5 and the pendent beam portion be forced down to its limit (see Fig. 2) and thereby maintain the point to its initial position, that is, in substantially the plane of the bottom of the runner or shoe, it being obvious that the movement of the sliding head will be upwardly in the standard when the said standard is swung forwardly to adjust the plow point so it retains the position with respect to the runner, as before referred to.

What I claim is:

1. In a plow, a plow carrying standard pivotally mounted at the plow end to swing backwardly and forwardly, and means for reciprocally moving the plow point with respect to the standard as the latter is adjusted in reverse directions.

2. In a plow having a fixed runner, a standard pivotally connected to the front end of the runner, a plow point carried by the standard and means for maintaining a relatively fixed relation between the plow point and the runner as the plow is adjusted to its digging positions.

3. In a plow of the character stated, the combination with the beam having a downwardly curved rear end, a runner fixedly mounted on said end and projected forwardly therefrom, a standard pivotally mounted on the front end of the runner, a plow point carried by the standard and means operable through the movement of the standard for effecting a sliding movement of the plow on the standard for the purposes specified.

4. In a plow of the character stated, the combination of a beam having its rear end curved downwardly to form a standard and a runner fixedly secured to the lower end thereof and projected forwardly therefrom, a plow carrying standard pivotally mounted in the front end of the runner, means on the standard and the beam for locking the plow standard to its set position and other means on the standard and the beam for sliding the plow on the standard as the said standard is shifted to its set positions.

5. In a plow of the character stated, a plow beam having its rear end curved downwardly, a runner fixedly secured thereto and projected forwardly from the said curved portion, a standard that straddles the beam and the runner and is pivotally secured to the front end of the runner, said beam having a pendent extension provided with a slot eccentric to the pivot of the standard, a head member slidably mounted on the lower end of the standard having a cross bolt that rides in the eccentric slot, and a plow point mounted on the lower end of the standard and bolted to the sliding head to move therewith.

EDWARD O. GAY.
